(57) **CLAIM**

The ornamental design for a curvilinear sided jewelry case, as shown and described herein.

DESCRIPTION

FIG. 1. Is a perspective view of my curvilinear sided jewelry case shown in the open position with the dotted lines showing being for illustrative purposes only for which no claim is made;

FIG. 2. Is a front perspective view of my curvilinear sided jewelry case as shown in the closed position;

FIG. 3. Is a top plan view thereof;

FIG. 4. Is a bottom plan view thereof;

FIG. 5. Is a front view thereof;

FIG. 6. Is a rear view thereof;

FIG. 7. Is a left side elevational view thereof with the right side being a mirror image thereof.
